UNITED STATES PATENT OFFICE.

WILLIAM E. GIBBS, OF WESTFIELD, MASSACHUSETTS.

MUCILAGE-STAMP.

SPECIFICATION forming part of Letters Patent No. 587,726, dated August 10, 1897.

Application filed March 11, 1897. Serial No. 626,927. (No model.)

To all whom it may concern:

Be it known that I, WILLIAM E. GIBBS, of Westfield, in the county of Hampden and State of Massachusetts, have invented a new and useful Improvement in Mucilage-Stamp, of which the following is a specification.

My invention relates to an improvement in mucilage-stamps, the object being to provide a device which may be caused to readily apply the mucilage upon any desired surface and at the same time laying the mucilage on smoothly and evenly and in just sufficient quantity to prevent it from unduly spreading.

A further object is to provide a device which will retain a supply of mucilage without allowing the mucilage to gum or harden, the stamp being so constructed that the reservoir for containing the mucilage may be readily and quickly filled with a fresh supply.

20 A still further object is to provide a stamp in which the sticky parts are thoroughly protected when not in use.

A practical embodiment of my invention is represented in the accompanying drawings, in which—

25 Figure 1 is a front view of the stamp. Fig. 2 is a side view of the same. Fig. 3 is a vertical central section in the plane of the line 3 3 of Fig. 1, and Fig. 4 is a similar section 30 showing the position of the parts when the stamp is being used for applying mucilage to a surface.

The supporting-stand is denoted as a whole by A, its neck through which the reciprocating plunger slides by a, and its legs by a'. The legs are preferably spread at their bases, as shown at a², to form a firm support for the stand. The vertically-reciprocating plunger consists of a head B and a shank C, which is 40 provided with a suitable operating knob or handle D.

The neck a is provided with a bore a³, through which the shank C of the plunger slides. The shank C is fitted to the bore a³ 45 of the neck a for a portion of the length of the shank near its upper end. The balance of the shank C is reduced in diameter, as shown at c, a shoulder c' being thereby formed, between which shoulder and an inwardly-projecting flange a⁴ on the neck a is interposed a spring E, which tends to return the shank to the limit of its upward movement when it

has been depressed. The shank C is of tubular form, its bore being denoted by c².

55 The head of the flange is hollow, thereby forming a reservoir b for the reception of the mucilage. This reservoir has a feather-and-groove connection with the legs a' of the support, as shown at a⁴, whereby it is guided in its upward and downward sliding movements. 60

The reservoir or head of the flange is connected with the stem of shank C by means of the coupling-nut F, which has a screw-threaded engagement with the exterior of the lower end of the shank C and a screw-threaded engagement with the interior of the top of the head D. This coupling-nut is provided with suitable openings f, whereby communication is established between the interior of the reservoir and the interior of the 70 shank.

A discharge-opening b' is formed in the bottom of the reservoir B, and beneath the said opening is secured in any suitable manner a mucilage-distributing pad G, which is of some 75 porous material—such, for instance, as felt or sponge. The mucilage-discharge opening b' is kept normally closed when the stamp is not in use by means of a valve H, which is yieldingly held in its seat by means of a spring h, 80 surrounding its upwardly-extending stem h' and extending between the head of the valve and the coupling-nut F. The coupling-nut F is provided with a suitable guide f' for the stem h' of the valve. The valve H is further 85 provided with a downwardly-extended stem h², which extends through the distributing-pad G and projects a slight distance below the same, so that when the plunger is forced down the said downwardly-extended stem h² 90 will be engaged by the surface to which the mucilage is to be applied and the valve H thereby raised away from its seat, allowing the mucilage to flow through the opening b' and permeate the porous pad G. 95

A swinging protecting pan or cap I is hinged at i to suitable lugs a⁵ on the legs a' of the supporting-stand in position to cover the pad G when the parts are in their normal position. The pan I is connected by means of 100 suitable straps i' with the sides of the reservoir B in such a manner that the downward movement of the said reservoir will swing the cap or pan outwardly away from the line of

movement of the said reservoir to permit the pad G to engage the surface beneath the stamp. These straps *i* are so connected that they will cause the pan I to automatically 5 return to its protecting position when the reservoir returns to its normal position.

An air-vent tube J extends through the bore *c*² of the shank C and is secured at its lower end to the guide *f*' on the nut F. The 10 upper end of the vent-tube J preferably extends beyond the top of the shank C, as shown at *j*.

The operating handle or knob D is removably secured to the top of the shank C. In 15 the present instance it is shown as having a screw-threaded engagement therewith.

When it is desired to fill the reservoir B, the handle D is removed and the mucilage is poured into the bore *c*² of the shank C. It 20 will run from there through the openings *f* in the nut F into the interior *b* of the reservoir. The air will escape freely through the vent-tube J, thereby permitting the reservoir to be rapidly filled. When the reservoir has 25 been filled, the handle D is again engaged with the shank C.

When it is desired to gum a surface, it is placed beneath the stamp and the reservoir is forced downwardly by depressing the handle D. This downward movement of the reservoir will swing the protecting-cover I away, as has been hereinbefore described, the valve H will be raised from its seat, the mucilage will fill the pad G, and from thence will be 35 applied to the surface.

The stamp as above described is very neat and clean and will keep the mucilage from gumming and at all times ready for immediate use.

40 It is evident that slight changes may be resorted to in the construction and arrangement of the several parts without departing from the spirit and scope of my invention. Hence I do not wish to limit myself strictly 45 to the structure herein set forth; but

What I claim is—

1. A mucilage-stamp comprising a suitable support, a reciprocating plunger mounted therein, the said plunger comprising a reservoir-head, a shank connected therewith, a 50 mucilage-distributing pad carried by the

head, a mucilage-discharge outlet for feeding the mucilage to the said pad and a valve under the control of the movement of the plunger for opening and closing the said mucilage-discharge outlet, substantially as set forth. 55

2. A mucilage-stamp comprising a suitable support, a reciprocating plunger mounted to slide therein, the head of the said plunger 60 forming a mucilage-reservoir, a mucilage-distributing pad carried by the plunger-head, a mucilage-discharge outlet in the head through which the mucilage is fed to the pad, a valve in position to normally close the said outlet 65 and a downwardly-extending stem carried by the valve in position to be engaged by the surface to be mucilaged as the plunger is depressed for raising the said valve away from its seat thereby permitting a portion of the 70 mucilage to pass through the discharge-outlet into the pad, substantially as set forth.

3. A mucilage-stamp comprising a suitable support, a reciprocating plunger mounted to slide therein, the said plunger comprising a 75 tubular shank and a hollow head communicating with the interior of the shank, an air-vent tube extending from the reservoir-head upwardly through the shank and a mucilage-distributing pad carried by said head in position to receive a supply of mucilage from the interior of the same substantially as set forth.

4. A mucilage-stamp comprising a suitable support, a reciprocating plunger fitted to slide 85 therein, the head of the said plunger forming a reservoir for the mucilage, a mucilage-distributing pad carried by the head in position to receive mucilage therefrom, and a swinging protecting-pan mounted upon the support having a connection with the head of the plunger whereby the reciprocating movement of the plunger is caused to swing the pan into position to cover the pad when the plunger is slid in one direction and away from the 90 said pad when the plunger is slid in the opposite direction, substantially as set forth. 95
